UNITED STATES PATENT OFFICE.

JOHN E. HILBISH, OF LA GRANGE, ILLINOIS, ASSIGNOR TO KELLOGG SWITCHBOARD AND SUPPLY COMPANY, OF CHICAGO, ILLINOIS, A CORPORATION OF ILLINOIS.

UNIVERSAL CORD CIRCUITS.

1,426,478.

Specification of Letters Patent. Patented Aug. 22, 1922.

Application filed January 30, 1919. Serial No. 273,970.

To all whom it may concern:

Be it known that I, JOHN E. HILBISH, a citizen of the United States of America, residing at La Grange, in the county of Cook and State of Illinois, have invented certain new and useful Improvements in Universal Cord Circuits, of which the following is a specification.

My invention relates to telephone systems and has to do more particularly with systems of the universal type in which universal cord circuits are provided for interconnecting telephone lines of different character such as magneto and common battery lines. The cord circuit of my invention may be used to connect a magneto line to a magneto line; a magneto line to a common battery line; a common battery line to a magneto line, and a common battery line to a common battery line.

A feature of my invention is the provision of a link circuit which may be used to establish any of the above-mentioned connections, and which cord circuit is provided with only single wound relays, thereby furnishing very efficient voice transmission.

The novel features of the invention through the provisions of which the above-mentioned and other advantageous results are attained will be more fully explained with reference to the accompanying drawing in which a preferred embodiment of my invention is shown. To the left of the accompanying drawing I show a calling common battery substation A terminating at the exchange in the line circuit L, which comprises the usual line relay LR, cut-off relay CO, answering jack J and line signal S. A magneto substation B is also shown terminating at the exchange in a line circuit L' comprising the usual drop signal DS and answering jack J'. A cord circuit C is provided which is adapted for interconnecting the different lines shown, the said cord circuit C being used in establishing connections between common battery and local battery lines; local battery and common battery lines; common battery and common battery lines, and local battery and local battery lines.

The cord circuit C comprises an answering plug AP and a calling plug CP, the said plugs being connected by the heavily marked conductors. The conductors have a repeating coil RC interposed, the said coil RC comprising windings 1, 2, 3 and 4, and the

said coils 1 and 2 are in suitable inductive relation with the coils 3 and 4. At the answering end of the cord circuit C, I provide a switching relay SW which is connected to the third contact of the plug AP and when the plug AP is connected to a common battery line, the switching relay SW operates to permit the energization of the supervisory relay SR which relay SR prevents the premature lighting of the answering supervisory lamp AL. When the plug AP is connected to a magneto line, the switching relay SW remains at normal due to the open condition of the third contact of the jack, so that when the magneto substation 70 operates his hand generator in sending a disconnect signal, the switching relay SW remains at normal allowing the disconnect relay DR to become energized momentarily to close a circuit for the supervisory relay 75 SR which in turn closes a circuit for the answering supervisory lamp AL to give the operator of the cord circuit C a disconnect signal. When the plug AP is connected to a jack J' of a magneto subscriber's line the 80 tip contact a' of the plug AP registers with the tip spring a of the jack J', the ring contact b' of the plug AP connects with the ring spring b of the plug J' and the sleeve contact c' of the plug AP registers with the 85 sleeve c of jack J'. When the plug AP of the cord circuit C is connected to the jack J of a common battery subscriber's line, the tip contact a' of the plug AP registers with the tip spring a' of the plug J, and the 90 sleeve contact c' of the plug AP registers with the sleeve contact c' of the jack J, the ring contact b' of the plug AP not registering with any contact of the jack J, but remaining on open circuit. A ring-back key 95 RB is provided for purposes which are well known in the art, and a listening key LK is also provided, which, when actuated, connects the operator's set O to the cord conductors.

The calling end of the cord circuit C is also provided with a switching relay SW', a disconnect relay DR' and a supervisory relay SR', the said relays performing the same functions as described in connection with 100 the answering end of the cord C. A calling supervisory lamp CL is also provided for the usual supervisory purposes. The calling end of the cord circuit C is also provided with a ringing key RK which, when actu- 105 110

ated, connects the ringing generator G to ring the call bell of a called-for substation. To the right of the drawing I show a common battery substation D terminating at the 5 exchange in a line circuit L² comprising the usual line relay LR', cut-off relay CO', jack J², and line signal S'. A magneto substation E is also shown terminating at the exchange in a line circuit L³ comprising the 10 usual drop-signal DS' and jack J³.

Having described in general the apparatus as illustrated in the drawing, the operation of the system will now be described in detail.

- 15 Assuming that a call is initiated at the common battery substation A, the subscriber at the substation in removing his receiver from the switch hook closed an energizing circuit for the line relay LR of line circuit 20 L over a circuit traced from battery through the winding of relay LR, normal contact 5 of relay CO, through the closed contacts of the substation switch hook and back to ground at normal contact 6 of relay CO.
- 25 The closing of alternate contact of relay LR causes the line signal S to glow, and the operator noting the lighted signal, inserts the answering plug AP of the cord circuit C into the jack J of the calling line. The 30 insertion of the plug AP into the jack J establishes an energizing circuit for the switching relay SW and the cut-off relay CO traced from battery through the winding of relay SW, conductor 7, normal contact 8 of relay SW, conductor 9, sleeve contacts of the connected plug AP and jack J to ground through the winding of the cut-off relay CO. The plug AP is so constructed that when it is inserted into the jack J of 35 40 a common battery line, the ring contact of the said plug AP is slightly smaller than the sleeve of the jack, thus placing the ring contact of plug AP in open circuit and allowing the tip and sleeve contacts of the 45 respective plug and jack AP and J to engage, thus utilizing a three-conductor plug as AP in connection with a two-wire line circuit as L. Upon the energization of relay CO its contacts 5 and 6 assume their 50 alternate position allowing the line relay LR to restore to efface the line signal S. Upon the energization of relay CO, an energizing circuit for supervisory relay SR is established over a circuit traced from battery through the winding of relay SW, its alternate contact 10, conductor 11, winding 2 of repeating coil RC, conductor 12, make-before-break contact 8, conductor 9, sleeve contacts of the plug AP and jack J, through 55 60 the closed contacts of the substation switch hook, back through the tip contacts of the connected plug AP and jack J, normal contact 13 of the ring-back key RB, winding 1 of the coil RC, conductor 14, alternate contact 15, and conductor 16 to ground through

the winding of supervisory relay SR. The contacts 8 and 10 of the relay SW are so adjusted that the contact 10 closes when the relay SW is energized before normal contact 8 is opened. The opening of normal contact 17 of relay SR prevents the premature lighting of the answering supervisory lamp AL. The closing of alternate contact 10 of relay SW closes a locking circuit for the relay SW over a circuit traced from battery through the winding of relay SW, its alternate contact 10, conductor 11, winding 2 of the induction coil RC, conductor 12, alternate contact 8, conductor 9, sleeve contacts of the plug AP and jack J to ground 80 through the winding of relay CO. The said relay SW after once energizing remains energized until the plug AP is removed from the jack J. The operator now actuates her listening key LK to connect her operator's 85 set O to the cord conductors and inquires the wants of the calling subscriber at substation A.

Assuming that it is the magneto substation E that is wanted, the operator inserts 90 the calling plug CP into the jack J³ of the called magneto line E. When plug CP is inserted into jack J³ no circuit is established for the switching relay SW', as the sleeve contact of the jack J³ is not connected to 95 any apparatus, therefore the switching relay SW' remains at normal. The operator now actuates the ringing key RK to connect the ringing generator G to transmit ringing current to ring the bell of the called-for subscriber at substation E, the ringing circuit being traced from the ungrounded pole of the generator, G, through alternate contact 18 of the key RK, tip contacts of the 100 connected plug CP and jack J³, through the call bell at the substation E back through the ring contacts of the plug and jack CP and J³ and conductor 19, to ground at alternate contact 20 of the key RK. The subscriber at the substation E in response to 105 his call bell removes his receiver and the subscribers at substations A and E are now in conversational circuit, the said talking circuit being traced over the heavily marked conductors.

Assuming that the subscribers have finished conversation, the restoration of the receiver at the substation A opens the circuit of the supervisory relay SR at the switch-hook contacts and the closing of normal contact 17 thereof establishes an energizing circuit for the answering supervisory lamp AL traced from battery, through normal contact 17, conductor 21, alternate contact 22, conductor 23, through the lamp AL to 120 ground. The lamp AL is lighted and notifies the operator that the subscriber at the substation A has replaced his receiver. The subscriber at the called magneto substation E replaces his receiver and actuates his 125 130

hand generator to send current over his line to the central office, the current from the generator being traced from the generator, through the tip contacts of the plug 5 CP and jack J², contact 18, winding 3 of coil RC, conductor 24, through the winding of the disconnect relay DR', conductor 25, normal contact 26 of relay SW', conductor 27, winding 4 of the coil RC, ring 10 contacts of the plug CP and jack J² to the other side of the generator at the substation E. The relay DR' is momentarily energized due to the impulse of current from the generator and the closure of alternate 15 contact 28 of relay DR' closes a circuit for relay SR' traced from battery through alternate contact 28 of relay DR', conductor 29, conductor 30, normal contact 31 of relay SW', conductor 32, through the winding 20 of relay SR' to ground. The closure of alternate contact 33 of relay SR' establishes a locking circuit therefor, traced from ground, through the winding of relay SR', conductor 32, normal contact 31, conductor 25 30, normal contact 34 of the listening key LK, conductor 35, normal contact 36 of relay SW', and conductor 37 to battery and ground at alternate contact 33 of relay SR'. The closing of alternate contact 33 30 of relay SR' also establishes an energizing circuit for the calling supervisory lamp CL from battery, through alternate contact 33, conductor 37, normal contact 36, conductor 35, normal contact 34, conductor 30, conductor 29, normal contact 28, and through the lamp CL to ground. The operator noting the two lighted supervisory signals AL and CL knows that conversation has 35 terminated and now actuates her listening key LK to open normal contact 34, which effaces the signal CL and also opens the circuit of relay SR'. The operator now withdraws answering and calling plugs AP and CP from their connected jacks. The 40 withdrawal of plug AP opens the circuit of switching relay SW and cut-off relay CO. The relay SW in restoring opens its alternate contact 22, thereby allowing the lamp AL to be effaced. The line circuits 45 50 L and L² are now at normal as is also the apparatus of the cord circuit C, and the said apparatus is now available for establishing other connections.

Now, if a call is initiated from the magneto substation B, the actuation of the hand generator thereat causes a flow of current to pass through the winding of the drop signal DS of the line circuit L'. A shutter of the drop signal DS is displayed to attract her attention and the operator noting the actuated drop signal, inserts the answering plug AP into the jack J' of the calling magneto line. The insertion of the plug AP in jack J' restores the drop shutter and also disconnects the winding of 55 60 65 the drop signal DS from across the line. The self-restoring drop may be of the type shown in Patent No. 697,515, granted April 15th, 1902. The operator now actuates the listening key LK to connect her operator's set O to the cord conductors and inquires the wants of the calling subscriber at the magneto substation B. The sleeve of the jack J' being disconnected from all apparatus, no circuit is established for the 75 switching relay SW, the said switching relay SW therefore remaining at normal. The operator having ascertained the wants of the subscriber at magneto substation B and assuming that it is the common battery 80 substation D that is wanted, the operator inserts the calling plug CP into the jack J² of the called common battery substation D, thus closing an energizing circuit for the switching relay SW' and the cut-off relay CO' of the line circuit L² the circuit being traced from battery through the winding of switching relay SW', conductor 40, the make-before-break contact 41, conductor 42, sleeve contacts of the connected plug 85 90 CP and jack J² to ground through the winding of the cut-off relay CO'. The contacts 26 and 41 of relay SW' are so adjusted that alternate contact 26 is closed to close a substitute circuit for relay SW' before normal 95 contact 41 is opened, and, of course, due to the make-before-break construction of the springs 41, after contact 26 is closed the alternate contact 41 is closed before normal contact 41 is opened. The closing of alternate contact 26 of the switching relay SW' establishes a locking circuit for itself traced from battery through the winding of the said relay SW', its alternate contact 26, conductor 27, winding 4 of the repeating 100 105 coil RC, conductor 43, alternate contact 41, conductor 42, sleeve contacts of the connected plug CP and jack J² and through the winding of the cut-off relay CO' to ground. The closing of alternate contact 44 110 of the switching relay SW' establishes an energizing circuit for the calling supervisory lamp CL traced from battery, through normal contact 33 of supervisory relay SR' conductor 45, alternate contact 44, conductor 115 46 and through the lamp CL to ground. The lamp CL remains lighted until the called subscriber answers.

The operator now actuates the ringing key RK to connect the ringing generator G 120 to ring the call bell of the subscriber at the common battery substation D, the said ringing current being traced from the ungrounded pole of the ringing generator G, through alternate contact 18 of the ringing key RK, 125 tip contacts of the connected plug CP and jack J² through the call bell and condenser at the substation D back through the ring contacts of the connected jack J² and plug CP, and conductor 19 to ground at alternate 130

contact 20 of the ringing key RK. The subscriber at the substation D in response to his call signal removes his receiver from its respective switch hook to close the switch-hook contacts. The closing of the contacts thereat establishes an energizing circuit for the supervisory relay SR' traced from ground through the winding of the said relay SR', conductor 32, alternate contact 31 10 of the switching relay SW', conductor 24, the winding 3 of the repeating coil RC, normal contact 18 of the ringing key RK, tip contacts of the connected plug CP and jack J², through the now closed contacts at the 15 substation switch hook of substation D, back through the sleeve contacts of the plug CP and jack J², conductor 42, alternate contact 41, conductor 43, winding 4 of the repeating coil RC, conductor 27 and alternate contact 20 26 of switching relay SW' to battery and ground, through the winding of the switching relay SW'. Upon the energization of the supervisory relay SR', its normal contact 33 is opened which brings about the effacement 25 of the calling supervisory lamp CL, notifying the operator that the called subscriber at the common battery substation D has answered. The talking circuit between the magneto substation B and the common battery substation D may be traced over the 30 heavily marked conductors.

When conversation is completed, the calling subscriber at the magneto substation B places his receiver upon its switch hook, operates his hand generator, transmitting current from the hand generator through the tip contacts to the connected jack J' and plug AP, normal contact 18, winding 1 of the repeating coil RC, conductor 14, through 35 the winding of the disconnect relay DR, conductor 50, normal contact 10 of the switching relay SW, conductor 11, winding 2 of the repeating coil RC, the ring contacts 40 of the connected plug AP and jack J' to the other side of the hand generator at the substation B. The relay DR is momentarily energized by this flow of current and the closure of its alternate contact 51 establishes 45 an energizing circuit for the supervisory relay SR traced from battery through alternate contact 51, conductor 52, normal contact 15 of the switching relay SW, conductor 16 to ground, through the winding of the supervisory relay SR. The supervisory relay SR upon energization closes a locking 50 circuit for itself traced from battery, through alternate contact 17 of the relay SR, conductor 53, normal contact 54 of the relay SW, conductor 55, normal contact 56 of the 55 listening key LK, conductor 52, normal contact 15 of relay SW, and conductor 16 to ground through the winding of the supervisory relay SR. A circuit for the answering supervisory lamp AL is also established 60 upon the energization of relay SR, traced 65

from battery, through alternate contact 17 of relay SR, conductor 53, normal contact 54 of relay SW, conductor 55, normal contact 56 of the listening key LK, conductor 52, normal contact 51 of relay DR, and through 70 the answering supervisory lamp AL to ground. The answering supervisory lamp AL is thus lighted, notifying the operator of the cord circuit C that the subscriber at the substation B has signaled for disconnect. 75 The subscriber at the called common battery substation D upon replacing his receiver upon its said switch hook opens the circuit for the supervisory relay SR' at the switch hook contacts, and the closing of normal contact 33 of relay SR' establishes an energizing circuit for the calling supervisory lamp CL, traced from battery, through normal contact 33 of relay SR', conductor 45, alternate contact 44 of switching relay SW', 80 conductor 46, and through the lamp CL to ground. The calling supervisory lamp CL is thus lighted and the operator noting the two lighted supervisory lamps AL and CL knows that conversation has terminated, and 85 actuates her listening key LK. The opening of normal contact 56 of relay LK opens the locking circuit for the supervisory relay SR and also opens the circuit for the answering supervisory lamp AL, thus effacing 90 the said lamp AL.

The operator now withdraws the answering plug AP and the calling plug CP from their respective jacks J' and J². The withdrawal of the calling plug CP from jack J² 100 opens the energizing circuit for the switching relay SW' of the cord circuit C and the cut-off relay CO' of the line circuit L². The relay SW' upon deenergizing opens its alternate contact 44 to efface the calling supervisory signal CL. The apparatus used in establishing the above-described connection is now at normal and available for use 105 in establishing other connections.

Should the magneto subscriber at the calling substation B wish to recall before the plugs have been withdrawn, the continued actuation of the hand generator at the substation B transmits alternating current through the disconnect relay DR. This 110 alternating current passing through the disconnect relay DR causes the said relay to chatter to open and close its alternate contact 51, thus producing a flickering effect of the answering supervisory lamp AL. This 115 distinctive flickering of the lamp AL notifies the operator that a recall is desired, distinguishing it from the steady glow of the answering supervisory lamp AL when a disconnect signal is given.

The operator in answering the recall actuates her listening key LK to open the normal contact 56, which restores the supervisory relay SR and effaces the supervisory lamp AL, and the operator having connected her 120 125

operator's set O may now converse with the recalling subscriber. The recall of the common battery subscriber is caused by the subscriber's switch hook being operated, causing the supervisory signal to flash, notifying the operator that the common battery subscriber wishes to recall. Should connection be established between the common battery substations A and D, the operation of the 10 circuit can be readily followed from the previous description, and likewise the connection between substations B and E is readily apparent from the foregoing description.

While I have described my invention in 15 one specific form, I do not wish to be limited to the same, as changes and modifications will readily suggest themselves to those skilled in the art, and I, therefore, aim to cover also such changes and modifications as 20 come within the spirit and scope of the appended claims.

What I claim as new and desire to secure by United States Letters Patent, is:

1. A telephone system including a subscriber's telephone line, a link circuit, a terminal for said link circuit for connecting said link circuit with said subscriber's line, a relay connected to a contact of said terminal and operable upon connection of said 25 terminal to said line to connect itself to another contact of said terminal as well as to the first contact of said terminal through contacts controlled by said relay, and a supervisory relay normally disconnected from said terminal, the connection of said supervisory relay with said terminal controlled by said first relay.

2. A telephone system including a subscriber's telephone line, a link circuit, a connection terminal for said link circuit for connecting the same to said subscriber's line, a relay for said link circuit connected through a normally closed contact of said relay to a contact of said terminal, a circuit 40 for said relay closed responsive to the connection of said link circuit to said line, and contacts controlled by said relay for connecting itself to another contact of said terminal without disconnecting itself from said 45 first contact, and a second relay normally disconnected from said terminal, the connection of said second relay and said terminal controlled by said first relay.

3. A telephone system including a subscriber's telephone line, a link circuit, a connection terminal for said link circuit for connecting the same to said subscriber's line, a supervisory signal, a relay for said link circuit connected to a contact of said terminal, a circuit for said relay closed responsive to the connection of said link circuit to said line, contacts controlled by said relay for connecting itself to another contact of said terminal, a second relay normally disconnected from said terminal, said second relay

connected to a third contact of said terminal by said first relay, to connect battery in circuit with said supervisory signal.

4. A telephone system including a subscriber's telephone line, a link circuit, a connection terminal for said link circuit for connecting the same to said subscriber's line, a relay for said link circuit connected to a contact of said terminal, a circuit for said relay closed responsive to the connection of 70 said link circuit to said line, contacts controlled by said relay for connecting itself to said first contact of the terminal and to another contact thereof, a second relay adapted to be connected to a third contact of said 75 terminal, and a source of current adapted to be bridged across said subscriber's line through the windings of said relays.

5. A telephone system including a subscriber's telephone line, a link circuit, a 80 three-conductor terminal for said link circuit for connecting the same to said subscriber's line, a relay connected to the third conductor of said terminal and adapted to be energized when said link circuit is connected to said subscriber's line, a second relay normally disconnected from said terminal, and contacts controlled by said first relay for connecting itself and said second relay to the talking conductors 85 of said terminal whereby talking current is fed to the subscriber's line.

6. A telephone system including a subscriber's telephone line, a link circuit, a three-conductor plug for said link circuit for 90 connecting the same to said subscriber's line, a supervisory relay normally out of circuit with said plug, a switching relay connected to a contact of said plug and operable when said link circuit is connected to said line to 95 include said supervisory relay in circuit with said plug, and means controlled by said switching relay for connecting itself to another contact of said plug and for connecting together the said contacts of said 100 plug.

7. A telephone system including a subscriber's telephone line, a link circuit for connection thereto, a supervisory signal for 115 said link circuit, a relay for said link circuit responsive to current transmitted over said subscriber's line by the subscriber at the substation thereon, a second relay responsive to the operation of said first relay, a locking circuit for said second relay independent of 120 the said first relay and a circuit for said supervisory signal maintained closed responsive to the de-energization of said first relay and the energization of said second relay, and also maintained opened if said first relay is energized and said second relay is in 125 its locked position to prevent the operation of said supervisory device.

8. A telephone system including a subscriber's telephone line, a link circuit for 130

- connection thereto, a supervisory signal for said link circuit, a relay for said link circuit adapted to be energized responsive to current transmitted over said subscriber's line by the subscriber at the substation thereon, a second relay adapted to be energized responsive to the operation of said first relay, a locking circuit for said second relay independent of the said first relay, and a circuit 10 for said supervisory device closed responsive to the de-energization of said first relay and the energization of said second relay, said supervisory device adapted to be intermittently operated by the intermittent actuation 15 of said first relay.
9. A telephone system including subscribers' lines of different character, a link circuit provided with plugs for interconnecting said subscribers' lines, a pair of supervisory 20 relays normally disconnected from said plugs, a pair of switching relays for said link circuit normally connected to said plugs and responsive to the connection of said plugs and said subscribers' lines to connect 25 said supervisory relays to said plugs, a pair of relays normally bridged across the con-
- ductors of said link circuit and responsive to current transmitted over the subscriber's line to effect the operation of said supervisory relays, and a manually controlled key 30 for controlling the circuits of said supervisory relays effected by the operation of said last pair of relays and the non-operation of said switching relays.
10. A telephone system including common 35 battery and local battery subscribers' telephone lines, a link circuit provided with a pair of plug terminals for interconnecting said lines, a pair of single-wound switching relays for said link circuit, a pair of supervisory 40 relays normally disconnected from said plug terminals, a pair of relays normally bridged across the conductors of said link circuit, a manually controlled key for controlling the circuits of said supervisory 45 relays, and supervisory devices controlled by said relays.

Signed by me at Chicago, county of Cook and State of Illinois, this 28th day of January, 1919.

J. E. HILBISH.
